UNITED STATES PATENT OFFICE

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT

ESCUTCHEON

Application filed May 19, 1930. Serial No. 453,544.

My invention relates to escutcheons for doors, and has special reference to such devices for sheet metal doors.

One of the objects of the present invention is to provide means of novel and improved construction for securing escutcheons to doors, especially sheet metal doors.

Another object of the invention is to provide means which are simple, strong and durable in construction for securing escutcheons to doors, especially sheet metal doors, whereby the escutcheons may be easily applied and when applied are securely and firmly held without danger of the securing means becoming loosened or otherwise de-ranged.

A further object of the invention is to provide novel and improved attaching means for escutcheons and other articles.

20 The several features of my invention, whereby the above-mentioned and other objects may be attained, will be readily understood from the following description and accompanying drawings, in which:

25 Figure 1 is a side view of a portion of a sheet metal door to which escutcheons and their securing means embodying the features of my invention in their preferred form are shown applied;

30 Fig. 2 is a detail sectional elevation taken substantially on the line 2—2 of Fig. 1;

Fig. 3 is a detail sectional elevation on a greatly enlarged scale showing especially the securing means for the escutcheons;

35 Fig. 4 is a detail side elevation of a portion of the securing means shown in Fig. 3;

Fig. 5 is a detail sectional plan view taken on the line 5—5 of Fig. 3, with one of the securing members removed; and

40 Figs. 6, 7 and 8 are views corresponding substantially to Fig. 2 but respectively showing three other modifications.

My improved escutcheons are shown applied to a sheet metal door 2 having an opening in its edge for receiving a lock case 4. The lock case is secured in place by screws 6 which are inserted through apertures in the projecting ends of the face plate 8 of the lock case, and screwed into projecting pieces 10 secured to the inner side of the edge wall of

the door. The escutcheons comprise plates 12 of any suitable form having apertures for receiving a pin tumbler lock cylinder 14 of the lock, and the shanks of knobs 16.

In accordance with the present invention, 55 one of the escutcheon plates 12 has a stud member 18 projecting from the inner side of each end portion, and the other escutcheon plate has similarly mounted socket members 20 adapted to receive the ends of the members 18. The end portion 22 of each stud member when the members are brought together, closely fits the outer end of the socket member 20, and the stud member is provided with a reduced projecting end 24. A gripping washer 26 is arranged within each socket member, and has a projecting tongue 28 that is loosely received in an aperture in the socket member, and a diametrically opposite tongue 30 extends through an elongated slot 32 in the socket member. A coiled spring 34 is arranged within the socket member between the bottom thereof and the washer 26 so as to tend to tip the gripping washer in one direction about the axis of the connection between the tongue 28 of the washer and the socket member. 70

To apply the escutcheon plates to the door the securing members 18 and 20 are inserted through apertures in the opposite sides of the door and the members 18 are caused to enter the ends of the socket members 20, the reduced ends 24 of the stud members being inserted through the gripping washers 26. The stud 75 and socket members are of the same diameter so that holes of the same size may be cut through the sides of the door to receive them, said members closely fitting the holes in the doors.

When the plates are thus applied and firmly pressed against the door and the securing members engaged, as above described, the springs 34 cause the gripping washers 26 to tip outwardly and thus to firmly grip the reduced ends 24 of the stud members. The two securing members are held firmly in alignment 85 by the close-fitting engagement between the portions 22 of the stud members and the outer end portions of the socket members.

When it is desired to remove the escutcheons for the purpose of replacement or repair, 100

it is merely necessary to remove the lock cylinder 14, knobs 16 and the lock case 4, whereupon by means of a suitable tool 36, inserted through the opening in the edge of the door, each lug 30 may be depressed against the tension of the spring 34 so as to release the gripping washer 26 from the reduced end of the stud member. The wall of each aperture 32 is provided with a clearance notch 33 to permit the end of the tool to easily engage the lug 30.

In case the escutcheon plates 12 are made of thin sheet metal, reinforcing strips 38 (Fig. 2) may be secured across the inner sides of the ends thereof by rivets 40, and the securing members 18 and 20 suitably riveted at 42 to the central portions of the strips 38, these central portions firmly engaging the sides of the doors when the escutcheons are applied.

20 In some cases, however, the ends of the securing members 18 and 20 may be directly riveted at 44 to the escutcheon plates (Fig. 6).

Also, if desired instead of riveting the securing members to the escutcheon plates, the outer ends of said members may be provided with heads 46 (Fig. 7) and the members merely inserted through apertures in the ends of the escutcheon plates, the heads abutting against the outer surfaces of the escutcheon plates.

30 In case the escutcheon plates are cast, the securing members may be cast integral therewith as shown in Fig. 8.

From the foregoing it will be apparent that by improved means for securing the escutcheon plates is simple, strong and durable, that the plates may be easily and quickly applied, and that when applied they are firmly and securely held.

40 While my improved attaching means is particularly adapted for attaching escutcheons to opposite sides of a door it will be apparent that it may be used for attaching but one escutcheon to a door and, moreover, for attaching various other articles. It will also be apparent to those skilled in the art that my invention permits various other modifications to be made without departing from the spirit thereof or the scope of the appended claims.

50 What I claim is:

1. Escutcheons of the class described having, in combination, two plates for opposite sides of a door, said door having an opening in its edge for receiving a lock, members projecting from the plates for insertion through apertures in opposite sides of the door, and means acting automatically when said members are inserted through said apertures to secure the members together, said apertures being in communication with said opening, and said securing means being so constructed and arranged as to permit it to be released by means of a suitable tool inserted through said opening.

65 2. Escutcheons of the class described hav-

ing, in combination, two plates for opposite sides of a door, a socket member projecting from one of said plates, a member projecting from the other plate adapted to enter said socket member, and means acting automatically when said members are thus engaged to secure the two members together comprising a gripping washer mounted for tipping movement in the socket member and adapted to receive the end of the other member, and a spring tending to tip said washer so as to cause it to grip the inserted member, said socket member being adapted to receive the spring and washer through the inner end thereof and being constructed to closely fit a portion of the other member.

3. Escutcheons of the class described having, in combination, two plates for opposite sides of a door, a socket member projecting from one of the plates, a member projecting from the other plate adapted to enter the socket member and provided with a portion fitting said socket member and a reduced end, a washer mounted in the socket member for receiving said reduced end when the members are brought together, a tongue and slot connection between the washer and the socket member so as to permit the washer to tip in one direction to grip said reduced end to hold the two members together, and a spring interposed between said washer and the bottom of the socket member tending to thus tip said washer.

4. Escutcheons of the class described having, in combination, two plates for opposite sides of a door, said plates being made of sheet metal, a reinforcing strip secured across the underside of each end of each of said plates, members secured to said reinforcing strips of the two plates for insertion through apertures in opposite sides of the doors, and means acting automatically when the plates are applied and said members are inserted through said apertures to secure said members together.

5. An attaching device of the class described comprising a socket member, a member adapted to enter said socket member, and means acting automatically when said members are thus engaged to secure the two members together comprising a gripping washer mounted for tipping movement in the socket member and adapted to receive the end of the other member, and a spring tending to tip said washer so as to cause it to grip the inserted member, said socket member being adapted to receive the spring and washer through the inner end thereof and being constructed to closely fit a portion of the other member.

6. An attaching device of the class described comprising a tubular socket member, a member adapted to enter the open inner end of said socket member, and means acting automatically when said members are thus

engaged to secure the two members together comprising a gripping washer mounted for tipping movement in the socket member and adapted to receive the end of the other member,
5 and a spring tending to tip said washer so as to cause it to grip the inserted member, said spring and gripping washer being insertable in said open inner end of said socket member, and said gripping washer and said
10 socket member having provision of means for holding the gripping member from outward movement.

In testimony whereof, I have signed my name to this specification.
